UNITED STATES PATENT OFFICE.

LOUIS F. LOHRENS, OF CHICAGO, ILLINOIS.

BURGLAR-ALARM LOCK AND DOOR-BELL.

1,296,982.

Specification of Letters Patent. Patented Mar. 11, 1919.

Application filed April 1, 1916, Serial No. 88,196. Renewed July 22, 1918. Serial No. 246,233.

To all whom it may concern:

Be it known that I, LOUIS F. LOHRENS, a citizen of the United States, residing at Chicago, in the county of Cook and State of Illinois, have invented certain new and useful Improvements in Burglar-Alarm Locks and Door-Bells, of which the following is a specification.

My invention relates to improvements in 10 burglar alarm locks and more particularly to such an alarm arranged to coöperate with a door guard of the slotted hasp and latch type, such as is commonly used for the purpose of providing a lock for holding the door 15 closed, and also a lock which will permit the door to be opened a few inches but will prevent it from being further opened.

The principal object of my invention is to provide in combination with such a lock an 20 alarm signal which will be actuated upon pressure being exerted upon the door, sounding an audible alarm, it being immaterial whether the door be bolted in its closed position or locked in its partially open position.

Another object of my invention is to provide an alarm in association with the hasp member of such a guard, the two button 25 latch commonly employed with guards of this character remaining unchanged. In my apparatus the latch member, this part being usually attached to the door, remains unaltered, whereas the hasp member secured to the casing is associated with the alarm bell so that when pressure is exerted thereon it is 30 free to move a slight distance before coming against a stop preventing further movement. This slight movement resulting from pressure being exerted on the door, as in an attempt to open it, will actuate the alarm.

As a further refinement of my invention I have provided in connection with the audible 35 alarm a door button positioned on the outside of the casing taking the place of the usual door bell button, pressure upon which will actuate the alarm. This enables the 40 audible signal to serve the double function of announcing the presence of a caller and also sounding an alarm should an unauthorized person attempt to open the door.

In the drawings wherein I have illustrated 45 a preferred embodiment of my invention;

Figure 1 is a horizontal sectional view 50 through a door and door casing showing my improved apparatus attached thereto, the 55 position occupied by the door and hasp be-

ing shown in dotted lines when the door is open.

Fig. 2 is a side elevation of the hasp and signal showing the hasp broken away at its pivot to illustrate the lost motion connection with its bracket.

Fig. 3 is a front elevation of the hasp and alarm as shown in Fig. 1.

Fig. 4 is a front elevation of the alarm mechanism showing the cover bell removed.

Fig. 5 is a vertical sectional view through the alarm mechanism at the rear of the gear train showing the control cam by means of which the alarm is permitted to ring a predetermined length of time after once being 70 actuated.

Fig. 6 is a vertical sectional view on the line 6—6 of Fig. 4, and;

Fig. 7 is a perspective view of the alarm actuating plunger and its control spring.

In the drawings the numeral 10 indicates a door adapted to close against the casing or jamb 11. Secured to the front face of the door near its free edge is a latch member 12 carrying at its inwardly projecting end a headed knob or button 13 and on its front face a rotatable button, such as is commonly employed with the ordinary type of guards of this character.

Mounted upon the jamb of the door adjacent the latch 12 is a plate 15 which overlies the molding 16 and is suitably secured thereto by means of screws 17. This plate is looped as at 18 and then turned outwardly to form a pivotal support, as at 19, for the hasp, the plate then being bent back upon itself, as at 20, to engage the inner face of the jamb of the door and provide an additional attachment member. The plate 15 at the point where it is doubled back upon itself, is cut away, as at 21, to receive the head 13 of the latch when the door is closed, the hasp 22 at that time overlying the outer face of the latch 12 in position for engagement through its slotted opening 23 with the rotatable button, or thumb bolt 14. The cutting away, as at 21, of the plate 15, provides upper and lower arms 24 to which the hasp is pivoted. Instead of providing circular apertures in the ends of the arms 24 in which to 95 pivot the pins 25—26 carried by the inner end of the hasp I have provided slots 27 so as to permit a slight relative movement of the hasp with respect to its mounting plate on lines perpendicular to the casing.

110

On a downwardly extending wing 28 of the plate 15 I have mounted an alarm mechanism comprising a base part 29 and bell 30. The bell is carried on the outer end of a central spindle 31 to which is secured one end of the coil spring 32. Through the train of mechanism indicated as at 33, the power stored by the spring is transmitted to an escapement pawl 34 which in turn actuates an arm 35 on the end of which is secured the hammer 36. The spring is wound by rotation of the bell 30, a suitable ratchet 37 being provided to hold the spring in its wound condition.

Actuation of the bell is secured through a reciprocable plunger 38 which is guidedly held in an upstanding lug 39 carried by the plate 15 and projects into the base part 29 of the bell. A pin 40 carried by the lower end of the plunger 38 engages the underside of the hammer arm 35 so that when in its raised position it locks the hammer against movement and consequently prevents ringing of the alarm. Downward movement of the plunger toward the axis of the bell releases the hammer and permits the escapement pawl 34 to vibrate the hammer.

The upper end of the reciprocable plunger 38 is beveled off, as at 41, for engagement with the downwardly projecting end 42, of the lower hasp pivot pin 26. A shoulder 43 is provided near the lower end of the pin 26 to prevent its vertical movement within its bearing slot 27. Obviously, outward movement of the pin 26 such as would result from an outward movement of the hasp due to an effort to open the door will depress the cam shaped end 41 of the plunger 38 thus permitting the bell to sound its alarm.

In order that the alarm may not be terminated immediately on cessation of pressure I have provided a mechanism by means of which the alarm once initiated will continue to ring for a predetermined length of time. This comprises a leaf spring 50 normally tending to pull the rod 38 into hammer release position and riveted to the casing as at 51 and extending in an arc to a point where its further end is connected to the lower end of the plunger 38. Intermediate its ends the spring is bent outwardly to form a cam like shoulder 52 which projects into the path of any one of a plurality of arms 53 carried by the spindle 31. On the outer end of these arms (in the particular embodiment shown I have illustrated three arms) is provided a nub 54, which when it engages with the cam surface 52 forces the spring outwardly and consequently raises the plunger stopping the bell. On the depression of the plunger incident to an attempt to open the door the hammer arm is released permitting the mechanism to commence its operation, thus forcing the arm

53 past the cam surface 52, the bell continuing to ring until the next succeeding cam arm 54 comes into engagement with the cam surface 52 and forces the plunger upwardly and outwardly, again locking the alarm 70 mechanism.

In order that this same alarm mechanism may be used as a manually operable door bell, this association being particularly valuable in connection with apartment kitchen doors and the like, where expense of installation is an important factor, I have provided a plunger 60 which projects outwardly through an opening in the frame of the door 80 and carries on its outer end a button 61 set in a recess 62 in the outer face of the door frame. An apertured plate 63 overlies the outer face of the button to prevent the spring 64 which is inclosed within the recess 62 from forcing the button 61 outwardly beyond the margin of the plate 63. The inner end of the plunger 60 is pointed or wedge shaped, as indicated at 65, in Fig. 6, for engagement with a notch 66 cut in the alarm actuating plunger 38. Pressure on the button 61 throws the wedge shaped end 65 of the plunger 60 against the lower side of the notch 66 in the alarm actuating plunger, thus moving it downwardly and initiating a signal.

Whereas I have illustrated and described a single embodiment of my invention it will be obvious that various changes may be made therein without departing from the spirit of the invention or the scope of the appended 100 claims.

Having described my invention, what I claim is:

1. The combination with a door and its casing of a door guard comprising a hasp, a latch on the door for association with the hasp to lock the door in either closed or partially open position, means for mounting the hasp carried by the casing to permit limited bodily movement as well as pivotal movement thereof, a signal, and means actuated by the bodily movement of the hasp to initiate the signal.

2. The combination with a door and its casing of a door guard comprising a hasp carried by the casing, a latch on the door for association with the hasp to lock the door in either closed or partially open position, means for mounting the hasp to permit limited bodily movement as well as pivotal movement thereof, a spring motor bell, a release for said spring motor, and means operated by the bodily movement of the hasp to actuate the release.

3. The combination with a door and its casing of a door guard comprising a hasp carried by the casing, a latch on the door for association with the hasp to lock the door in either closed or partially open position, a support for the hasp having an opening

therein, a pivot pin carried by the hasp and engaging the said opening, the pin being smaller than the opening to permit relative movement therein, a signal, and means actuated by the bodily movement of the pin within the opening to initiate the signal.

4. The combination with a door and its casing of a door guard comprising a hasp carried by the casing, a latch on the door for association with the hasp to lock the door in either closed or partially open position, a support for the hasp, having a slot therein extending perpendicularly to the door frame, a pivot pin carried by the hasp and engaging the slot, a signal, and means actuated by the bodily outward movement of the pin within the slot to initiate the signal.

15 5. The combination in a door guard com-

prising a slotted hasp for attachment to a door casing and a latch for attachment to a door, of a pivotal mounting for said hasp permitting free pivotal movement when not engaged by the latch and a slight limited bodily movement in a plane substantially perpendicular to the plane occupied by the door when closed, and means actuated by the bodily movement of the hasp to initiate a signal.

In testimony whereof I hereunto set my hand in the presence of two subscribing witnesses.

LOUIS F. LOHRENS.

In the presence of—

STANLEY W. COOK,
MARY F. ALLEN.
